UNITED STATES PATENT OFFICE.

WILLIAM T. ADAMS, OF BALTIMORE, MARYLAND.

ASH-SIFTER.

SPECIFICATION forming part of Letters Patent No. 297,737, dated April 29, 1884.

Application filed December 10, 1883. (No model.)

To all whom it may concern:

Be it known that I, WILLIAM T. ADAMS, a citizen of the United States, residing at Baltimore city, State of Maryland, have invented 5 certain new and useful Improvements in Ash-Sifters, of which the following is a description.

Figure 1 is a view of the device in the position occupied in sifting the ashes, the end of the case being removed. Fig. 2 is the same 10 view, showing the position of the parts when dumping the coals; and Fig. 3 is a longitudinal section of the sifting-receptacle.

My invention relates to ash-sifters of that 15 class which are inclosed within a case or box to prevent the dust from escaping, and more particularly to that form of ash-sifter which I have already described in my Patent No. 292,588, dated January 29, 1884.

The object of the present invention is to im- 20 prove the form of the said sifter and increase its holding capacity within a given size of box-space, as will be fully described herein-after.

In the drawings, A represents the outer 25 case or box, which is provided with a lid or cover, B, hinged at the back at a. Just below this lid and a little lower than the side walls of the box is a stationary or permanent top, C, having a hole through it closed by a smaller 30 hinged lid, D.

E is a screening-receptacle for coal-ashes, which is formed with solid heads at its ends, and a somewhat cylindrical body composed of galvanized wire-netting of a mesh large enough 35 to separate the unburnt coal from the ashes; or it may be of perforated sheet metal. This receptacle has an opening at its upper side, at d, through which the coal-ashes are inserted, and one of its sides is bent to form a spout, 40 through which the coals are dumped after the ashes have been sifted away from the same. This ash-receptacle is provided with a central shaft, E³, and said shaft is hung in the sides of the box or case, so as to permit the receptacle 45 to be oscillated. Instead of a shaft running all the way through, trunnions at the ends may be employed. One of the heads, E², of the ash-receiver is connected by a link-bar, F, with the lid or cover B, so that the elevation of this 50 cover turns the ash-receptacle so that its opening registers with the opening in the stationary top of the box, as shown in Fig. 1, to per-

mit ashes to be dumped from a hod into the screening-receptacle, which receptacle is oscillated to effect the screening of the coals from 55 the ashes by the oscillation of the lid B, which imparts its motion to the screening-receptacle through the connecting link-bar F. To permit the lid D to shut down tight, the cover C is provided with a slot, e, above one end of the 60 receptacle, to give passage to the bar F in connecting with the said receptacle.

In the lower part of the box or case is arranged a partition, G, which forms two receptacles, G' G², of which G' is for the refuse ashes, 65 and G² for the screened coal. In these receptacles G' G², I may use drawers to receive the ashes and coal, or I may use drawers without any dividing-partition, as the adjacent sides of the drawers will sufficiently act as a parti- 70

Just above the coal-receptacle is a hinged leaf or chute-board, H, hinged at one end to the side of the box and extending downwardly to a position above the top of the partition-board G, or the separating-line between the coals and ashes. This hinged leaf or chute-board is connected by a link-bar, I, with one of the ends or heads, E', of the screening-receptacle, and preferably the opposite head from 80 the one which is connected to the lid. When the screening-receptacle is in position for sifting the ashes, this leaf H acts as a chute to conduct the ashes to the ash-compartment, and also as a cover to the coal-receptacle to prevent ashes from getting mixed with the coal, and when the screened coal in the sifter-receptacle is to be dumped this leaf is let down by the turning of the sifter-receptacle to open the coal-receptacle and allow the coal to be dumped 85 90 95 100 therein from the nearly-inverted sifter-receptacle.

In operating the device the lid B is raised, which brings the opening in the sifter-receptacle into registration with the opening in the 95 stationary top beneath lid B, and also causes the hinged leaf or chute-board to close the top of the coal-receptacle. The small lid D is then raised and thrown back to a position where it acts as a supporting-brace to hold up lid B, 100 while the coal is dumped from the hod into the screen or sifter receptacle. After this is done, the lid D is closed to make the the case tight against the escape of dust, and the lid B

is vibrated. This imparts through the link-bar a vibratory action to the sifter-receptacle that separates the dust from the coal therein, and allows the dust to gravitate to the ash-receptacle. Then, to dump the coal out of the screen or sifter receptacle, the lid B is closed down. This action through the link-bars inverts the said sifter-receptacle, and at the same time opens the top of the coal-receptacle and allows the coal to fall therein.

In defining the relation of this application to the patent already granted me I would state that I am aware that there are features in common to both, and I claim nothing in this case that is claimed in the other.

Having thus described my invention, what I claim as new is—

1. The sifter or screen made in the shape of a cylindrical receptacle having a longitudinal opening, and hung centrally upon bearings in the case, combined with the case and bearings,

the lid B, and a link-bar connecting the two for oscillating and inverting the sifter, as shown and described.

2. The combination, with the case A and the hinged lid B, of the stationary top having smaller hinged lid D, adapted to sustain and form a brace for the lid B when they are opened, as described.

3. The combination, with a containing-case having two compartments in its bottom, of a hinged lid, B, a vibrating screen, a link-bar connecting the hinged lid to the vibrating screen, a hinged chute-board covering the coal-compartment, and a link-bar connecting the screen to the chute-board for the simultaneous operation of the lid B, screen, and chute-board, substantially as shown and described.
